UNITED STATES PATENT OFFICE.

CONRAD BIRGBAUER, OF DETROIT, MICHIGAN.

DIAMOND-MOUNTING.

1,273,992.

Specification of Letters Patent Patented July 30, 1918.

Application filed March 16, 1916. Serial No. 84,574.

To all whom it may concern:

Be it known that I, CONRAD BIRGBAUER, a citizen of the United States of America, residing at Detroit, in the county of Wayne 5 and State of Michigan, have invented certain new and useful Improvements in Diamond-Mountings, of which the following is a specification, reference being had therein to the accompanying drawings.

10 This invention relates to diamond mountings, and more particularly to that class of diamond mountings or stone holders used as tools for surfacing, trimming or grinding emery wheels.

15 The primary object of my invention is to provide a diamond mounting which may be adjusted to hold a diamond or similar stone in a desired position, the mounting embodying a socket or seat member which may be 20 adjusted to a desired position prior to permanently anchoring a diamond or other stone in the mounting.

Another object of my invention is to provide a mounting for stones of various sizes 25 and shape, and to hold a stone in such a manner that it may be firmly anchored in its mounting to present a desired grinding or cutting edge or point.

A further object of my invention is to 30 provide a diamond mounting wherein the parts are constructed with a view of reducing the cost of manufacture and at the same time retaining the features by which safety, accuracy, durability and simplicity 35 of construction are secured, and with such ends in view my invention resides in the novel constructions and arrangement of parts hereinafter fully described and then claimed.

40 Reference will now be had to the drawings, wherein—

Figure 1 is a longitudinal sectional view of a diamond mounting in condition to receive a diamond or other stone;

45 Fig. 2 is a view of the outer end of the mounting;

Fig. 3 is a longitudinal sectional view of the diamond mounting, showing the dia-

mond or stone in position and the mounting ready to be filled and finished;

50 Fig. 4 is a similar view of a completed mounting;

Fig. 5 is a side elevation of the same;

Fig. 6 is an elevation of a modified form 55 of mounting, partly broken away and partly in section;

Fig. 7 is a similar view of a further modification of my invention, and

Figs. 8 and 9 illustrate a still further 60 modification of my invention.

In describing my invention by aid of the various views above referred to, I desire to point out that the same are intended as merely illustrative of examples whereby my invention may be applied in practice, and 65 I do not confine my invention to any precise form shown. The following description is therefore to be broadly construed as including substitute constructions and arrangement of parts which are the obvious equivalent of those to be hereinafter referred to. 70

In the drawings, 1 denotes a holder body having the inner end thereof reduced to 75 form a cylindrical shank or stem 2 by which the holder body may be conveniently held and positioned relative to an emery wheel or the surface to be ground by the diamond mounting.

The holder body 1 has a bore or recess 3 with the walls thereof screw threaded to 80 receive an adjustable socket member 4. This member provides a seat 5 having the bottom thereof open and in communication with the bottom of the bore or recess 3, and the outer end of said member is formed with 85 a plurality of malleable prongs or lugs 6 adapted to be bent into engagement with a diamond or stone 7 to retain the same upon the seat 5 of the socket member. The diamond 7 is of that character ordinarily 90 used for surfacing emery wheels and in its partially cut condition it is held upon the seat 5 with a portion thereof protruding outwardly at the ends of the prongs or lugs. This is best shown in Fig. 3, and after the 95 socket member 4 has been properly posi-

tioned within the holder body 1, a convexo-concave cap 8 is screwed or otherwise mounted in the bore or recess 3 on the prongs or lugs 6 of the socket member 4, 5 said cap having a central opening 9 providing clearance for the protruding portion of the diamond 7, and side openings or recesses 10 adapted to accommodate a spanner wrench or suitable instrument employed for 10 rotating and seating the cap upon the socket member 4.

The properly located and anchored socket member is permanently fixed in the bore or recess 3 by pouring molten brass, aluminum 15 and brass, or other material designated 11, through the opening 9 of the cap 8 to fill the bore or recess 3 and such spaces as surround the diamond or stone 7.

After the socket member 4 and its stone 20 has been permanently fixed in the holder body 1, the outer end of the holder body is cut away or ground down, as indicated at 12, until the outer end of the holder body is flush with the convex side of the 25 cap 8, as shown in Fig. 4, and then the diamond mounting is ready for use.

The construction just described possesses many advantages compared to diamond mountings now in use. In the first place, 30 the adjustability of the socket member 4 permits of said socket member being correctly positioned within the holder body to avoid cutting away or grinding down a great deal of the holder body, and of course the location of the socket member depends upon the size and shape of the stone held thereby. Second, the lugs or prongs 6 can be easily 35 bent into engagement with the diamond or stone without injury to the same, and when the cap 8 is screwed into engagement with the prongs or lugs, said prongs or lugs are further pressed into engagement with facets or portions of the diamond. Third, the threaded walls of the bore or recess 3 pre- 40 sents a roughened surface on which the molten brass, used as a filler, may obtain a firm purchase and thus prevent the socket member from accidentally shifting within the holder body.

50 In Fig. 7 of the drawing, there is illustrated a slight modification of my invention wherein a shank or stem 13 is exteriorly screwthreaded and the outer end thereof provided with a socket 14 and prongs or lugs 55 15 adapted to be bent into engagement with a stone 16 placed in the socket 14. On the shank or stem 13 may be screwed a holder body 17 and after the holder body has been correctly positioned relative to the outer end 60 of the stem, a cap 18, similar to the cap 8, may be screwed in the detachable holder body 17, and then said holder body and the socket 14 provided with a filler and the

holder body ground down. This form of diamond mounting permits of the shank or 65 stem 13 being repeatedly used and after a filler is placed in the holder body 18, the stone is held just as firmly as in the preferred form of construction.

Another modification of my invention is 70 illustrated in Fig. 6, showing a holder body 19 having a recess 20 in which is placed a socket member 21, said socket member having a recess 22 and prongs 23 for holding a stone 24. The socket member 21 is of less 75 diameter than the recess 20 and said socket member can be positioned at a desired angle or inclination within the recess 20 and held in such position by screws 25 carried by the holder body 19. The screws 25 have the inner ends thereof pointed or beveled, as at 26, to engage on the prongs or lugs 23 of the socket member 21 and hold the socket member 21 so as to center the point or a certain portion of the stone 24 relative to the holder 85 body 19. A filler 27 may be placed in the recess 20 to permanently anchor the socket member 21, the filler also entering the recess 22 and surrounding the screws 25. The end of the holder body 19 may then be 90 ground down and in some instances portions of the screws 25 may be ground in order to expose a desired portion of the stone 24 at the convex end of the holder body.

Figs. 8 and 9 illustrate a further modification of my invention wherein a shank or 95 stem 28 has the outer end thereof provided with an oblong recess or socket 29 to receive an oblong stone 30. This stone may be correctly positioned by a plurality of radially 100 disposed screws 31, a filler 32 employed to permanently anchor the stone 30 and then the outer end of the stem or shank ground down similar to the holder body shown in Fig. 6.

105 It has been found that either of the forms illustrated and described practically serve the purpose for which they are intended and it is optional with a manufacturer as to what type of holder to use when mounting a diamond; the form of holder greatly depending upon the shape and nature of the diamond or stone to be mounted.

What I claim is:—

1. A diamond mounting comprising a 115 holder body, a socket member screwed therein and adapted to hold a diamond, a cap screwed in said holder body on said socket member and adapted to cooperate therewith in holding a diamond, and a filler in said 120 holder body against said socket member.

2. A diamond mounting comprising a 125 holder body, a socket member screwed therein, prongs forming part of said socket member and adapted to retain a diamond in said socket member, a cap screwed in said

holder body on said prongs, and a filler adapted to permanently anchor said socket member, said cap and the diamond held by said socket member and cap within said holder body.

3. A method of making a diamond tool, consisting first in providing a holder body with a cavity, then a socket member in which a diamond is mounted, placing the socket

member within the cavity of the holder body, ¹⁰ and then securing the socket member in the holder body by a sealing material.

In testimony whereof I affix my signature in presence of two witnesses.

CONRAD BIRGBAUER.
